APPARATUS FOR HAIR DYEING

Fred Kaul, Buenos Aires, Argentina

Application August 6, 1952, Serial No. 302,861

5 Claims. (Cl. 132—12)

1

This invention relates to apparatus for hair-dyeing.

It is an object of the present invention to provide an apparatus for hair-dyeing wherein the dyestuff is applied to the hair without staining the scalp or other parts of the skin.

It is another object of the present invention to provide an apparatus for hair-dyeing which comprises a toothed-plate adapted to receive the strands of hair to be dyed and which is intermediate the scalp and a pair of rolls containing the dyestuff.

Other objects of the invention are to provide an apparatus for hair-dyeing bearing the above objects in mind, which is of simple construction, inexpensive to manufacture, pleasing in appearance, compact, will have long life and which is easy to operate and efficient in operation.

For other objects and for a better understanding of the invention, reference may be had to the following detailed description taken in connection with the accompanying drawing, in which:

Fig. 1 is a perspective view of an apparatus embodying the features of the present invention and showing the same in an unfolded position;

Fig. 2 is a vertical sectional view taken along line 2—2 of Fig. 1;

Fig. 3 is a top plan view of the apparatus and showing the same in a folded, operative position and

Fig. 4 is a vertical sectional view taken along line 4—4 of Fig. 3 and showing the apparatus being applied to the hair.

Referring now in detail to the figures, and in the practice of my invention, there is shown a plate 10 of metal or any other suitable material having teeth 11 on opposite longitudinal sides thereof. The plate 10 is similar to the toothed plate of a safety-razor, but is larger and has longer teeth, and is further provided integrally with an elongated handle 12 having an opening 13 for a purpose to be hereinafter described and extending substantially transverse to the side edges of the teeth.

The handle 12 is pivotally secured to a second elongated handle 14, similarly provided at its end with an opening 15 in alignment with the opening 13, by means of a rivet 16, as clearly shown in Fig. 2. The handle 14 is of the same material as the handle 12 and is equal in length to the combined length of the handle 12 and plate 10, and is adapted to coincide with the latter parts when rotated to the position shown in Fig. 3. A slide ring 17 movably surrounds the handles 12 and 14 and is manually operable to the position shown in Fig. 3 whereby to maintain the handles

2

12 and 14 in operative engagement with each other.

The handle 14 is further provided at its end remote from the opening 15 with a pair of outwardly extending arms 18 and 19 at each side thereof, the arms extending outwardly therefrom at substantially right angles thereto and carrying at their respective ends pins 19' for rotatable rolls 20 and 21, which pins 19' extend substantially parallel to the longitudinal axis of the handles and at equidistant positions from the handle 14, the ends of the rolls being provided with openings adapted to receive the said pins 19' of the arms. The rolls 20 and 21 are formed of an absorbent material and are impregnated with the dyestuff being applied to the hair. The rolls 20 and 21 are spaced from the handle 14 sufficiently to coincide with the teeth 11 of the plate 10 when the handles are in operative engagement as shown in Fig. 3.

In operation, after the rolls 20 and 21 have been impregnated with dyestuff, the apparatus is closed sideways like a fan and the slide ring is moved to the position shown in Fig. 3. Thus the handle 14 carrying the rolls 20 and 21 and the handle 12 carrying the plate 10 are firmly united and the rolls 20 and 21 are held in their position on the teeth 11, as shown in Fig. 3. The apparatus is now ready for use in the following manner:

Taking hold of the combined handles 12 and 14, the apparatus is passed through the hair in such a way that the plate 10 rests on the skin, whilst the rolls 20 and 21 remain on the outside of the plate. The dye-impregnated rolls are thus separated from the skin by the plate, as shown in Fig. 4. By moving the apparatus in the direction opposite to the hair, the hairs automatically place themselves between the teeth 11 and are in contact with the rolls 20 and 21. Thus, the dyestuff impregnated in the rolls 20 and 21 dyes the hair without touching or staining the scalp or other parts of the skin.

It should now be apparent that there has been provided a novel apparatus for hair-dyeing which isolates the dyestuff and prevents the same from contacting or staining the scalp or other parts of the skin.

While various changes may be made in the detailed construction, it shall be understood that such changes shall be within the spirit and scope of the present invention as defined by the appended claims:

Having thus set forth and disclosed the nature of my invention, what is claimed is:

1. An apparatus for hair-dyeing comprising a

plate, said plate having teeth along each longitudinal edge thereof, an elongated handle secured to said plate, said handle at the end remote from said plate having an opening, a second elongated handle, said second elongated handle being substantially equal in length to the combined lengths of said plate and said first handle and being further adapted to coincide with said plate and first handle, said second handle having an opening at one end in alignment with said opening in said first handle, means located within said aligned holes for pivotally securing said first and second handles together whereby said first and second handles may be opened and closed in a fan-wise manner, means surrounding the said first and second handles for holding the latter in closed position, and a pair of rolls rotatably mounted on said second handle at the end remote from said opening therein, said rolls being adapted to coincide with said teeth of said plate when said handles are in closed position, said rolls being formed of an absorbent material whereby to absorb dyestuff.

2. An apparatus for hair-dyeing comprising a metal plate, said plate having elongated teeth along each longitudinal edge thereof, a first elongated handle secured to said plate, said handle at the end remote from said plate having a first opening, a second elongated handle, said second elongated handle being substantially equal in length to the combined lengths of said plate and first handle and adapted to coincide therewith, said second handle having an opening at one end in alignment with said opening in said first handle, a means located within said aligned holes to pivotally secure said first and second handles together, a slide ring movably surrounding said first and second handles, said slide ring being adapted to move longitudinally along said first and second handles to an open position adjacent the said pivot means and a closed position adjacent the said plate, and a pair of rolls rotatably mounted on said second handle at the end remote from said opening therein, said rolls being of an absorbent material whereby to absorb dyestuff and being adapted to coincide with said teeth of said plate when said first and second handles are in coincided relationship.

3. An apparatus for hair-dyeing comprising a metal plate, said plate having teeth on two opposite sides, a handle secured to said plate, a second handle, pivot means for joining the said handles at the ends thereof, at least one movable roll rotatably mounted on said second handle at the end remote from the said pivot means, said roll being formed of an absorbent material suitable for holding a dyestuff, and a slide ring embracing said handles whereby by moving said slide ring towards the said plate the apparatus is closed and by moving said slide ring towards the said pivot means the apparatus is opened.

4. An apparatus for hair-dyeing comprising a plate, said plate having elongated teeth along the opposite, longitudinal sides thereof, a first elongated handle secured to said plate, said handle at the end remote from said plate having an opening, a second elongated handle, said second elongated handle being substantially equal in length to the combined lengths of said plate and

said first handle and adapted to coincide therewith, said second handle having an opening at one end in alignment with said opening in said first handle, a rivet located within said aligned holes whereby to pivotally connect the ends of said handles remote from said plate, a slide ring surrounding said handles intermediate said rivet and said plate, two pair of spaced, outwardly extending arms secured to said second handle at the end remote from said rivet and at each side thereof, said arms extending outwardly therefrom at substantially right angles thereto, said arms carrying oppositely disposed pins at their free ends, a pair of rolls having openings at their respective ends receiving the said pins for rotatably mounting of the said rolls thereon, said rolls being formed of an absorbent material whereby to absorb a dyestuff, said arms being adapted to rotatably support said rolls in a coinciding position with said teeth of said plate when handles are closed by the movement of said slide ring to a position adjacent said plate.

5. An apparatus for hair-dyeing comprising a plate, said plate having elongated teeth along the opposite, longitudinal sides thereof, a first elongated handle integrally formed in said plate at one lateral side and extending therefrom substantially transverse to the side edges of said teeth, said handle at the end remote from said plate having a substantially circular opening therethrough, a second elongated handle, said second elongated handle being substantially equal in length to the combined lengths of said plate and said first handle and adapted to coincide therewith, said second handle having a second substantially circular opening therethrough at one end thereof, said second opening being in alignment with said opening in said first handle, a rivet located within said aligned holes whereby to pivotally connect the ends of said handles remote from said plate, a manually operable slide ring surrounding said handles intermediate said rivet and said plate a pair of spaced, outwardly extending arms integrally formed in said second handle at the end remote from said rivet and at each side thereof, the free ends of said arms carrying pins substantially parallel to the longitudinal axis of said handles and at equidistant positions from the said second handle, a pair of rolls having openings at their respective ends receiving the said pins for rotatably mounting the said rolls thereon, said rolls being formed of an absorbent material whereby to absorb a dyestuff, said arms being adapted to support said rolls adjacent said teeth when said handles are closed by the movement of said slide ring to a position adjacent said plate, said rolls being adapted to resiliently engage the hair between said teeth and said rolls whereby to transfer the dyestuff from said rolls to the hair without contacting the scalp.
